(57)

CLAIM

The ornamental design for an transaction card, as shown and described.

DESCRIPTION

FIG. 1 is a perspective view of a transaction card showing our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines in the drawings depict portions of the transaction card that form no part of the claimed design.

1 Claim, 3 Drawing Sheets
